UNITED STATES PATENT OFFICE.

JOSEPH REGENSTEIN, OF CHICAGO, ILLINOIS.

DOOR PANEL AND THE LIKE.

1,351,488.

Specification of Letters Patent. Patented Aug. 31, 1920.

Application filed June 27, 1919. Serial No. 307,080.

To all whom it may concern:

Be it known that I, JOSEPH REGENSTEIN, a citizen of the United States, residing at Chicago, in the county of Cook and State of Illinois, have invented certain new and useful Improvements in Door-Panels and the like, of which the following is a specification.

The present invention has to do with improvements in door panels such as are used in the finishing of doors for automobiles and other vehicles. While the type of door panel to which the present invention relates is very well adapted for use in connection with the manufacture of doors for automobiles and other vehicles, still it is not limited to such use, and is merely mentioned by way of example.

In Letters Patent of the United States, No. 1,259,287, issued to me March 12, 1918, for improvements in door panels and the like, I have disclosed a construction of door panel which is faced on one of its surfaces and which has its edge portion reinforced so that moisture cannot easily find its way between the body of the panel and said facing. The present invention has to do with an improvement whereby the back face of the panel is also protected or faced so that moisture cannot penetrate through the body of the panel and thus find its way between the body and the first mentioned facing.

Referring to the drawing:

Figure 1 shows a face view of a door panel embodying the features of the present invention;

Fig. 2 shows a fragmentary view of the edge portion of a modified construction of panel on enlarged scale;

Fig. 3 shows a back face view corresponding to Fig. 2, a portion of the back facing being broken away;

Fig. 4 shows a view corresponding to Fig. 2 of a modified form of edge protection; and

Fig. 5 is a view taken on the line 5—5 of Fig. 4 looking in the direction of the arrows and on considerably enlarged scale.

The door panel in its entirety is designated by the numeral 6. The body 7 of the panel comprises a sheet or plate of cardboard or the like of suitable contour and form. On its front face 8 said cardboard is provided with a facing or covering of facing material preferably of waterproof nature and pleasing appearance. Ordinarily

said facing 8 will be attached to the body 7 by paste or glue, and it is therefore desirable to be able to protect the panel so as to prevent the entrance of moisture between the body and the facing, since such moisture would soon loosen up the facing and cause deterioration of the panel.

In order to effectually prevent the entrance of moisture through the edge portion of the panel, I provide a reinforcement or protection such as a line of stitching 9 which passes through the body 7 and the facing 8; or in some cases I provide a binding strip 10 which overlaps the edges of both the backing and the facing material, and may be held in place by means of a line of stitching 11.

It will be observed that with the arrangement so far described it is in some cases possible for moisture to find its way through the body 7 from the back face thereof, such moisture soaking through the pasteboard or cardboard or other material and eventually resulting in deterioration of the entire panel. I have therefore, in the present case, provided a back facing or protection 12 so as to effectually prevent the possibility of such moisture working through the panel. This back facing may take the form either of a sheet of waterproof material, such as parchment, pasted to the back of the body 7 and having its edge portion protected by the stitching or binding strip; or in some cases may take the form of a layer or coating of waterproof paint or the like. In any case, however, it will be observed that the presence of the waterproof coating on the back side of the panel bears a very distinct and definite relationship to the presence of a sheet pasted or glued to the front face of the panel, since the entrance of moisture between the body and the front face, by passage through the material of the body, is thereby prevented.

I claim:

1. As a new article of manufacture, a door panel or the like comprising a backing of paste-board and the like, having pasted to its exposed surface a facing of suitable material, and having pasted or glued to its back surface a facing of water-proof material, and a line of stitching extending around the periphery of the panel and through the backing and both facing materials and serving to firmly secure the facing materials to the backing and prevent the entrance of wa-

ter into the edge of the panel, substantially pasted or glued to its back surface another facing of water proof material, and a line as described.

2. As a new article of manufacture, a door panel or the like comprising a backing of 5 paste-board or the like, having pasted or glued to its exposed surface a facing of suitable water - proof material, and having

1 facing of water proof material, and a line of stitching extending around the periphery 1 of the panel and through the backing and both surfaces thereof, for the purpose specified.

JOSEPH REGENSTEIN.
